UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

MEANS AND METHOD FOR SEALING BOXES AND THE LIKE.

Application filed November 5, 1926. Serial No. 146,496.

- This invention relates to means and methods for sealing boxes. In the accompanying drawings which serve to illustrate the invention:
- 5 Fig. 1 is a view of the several parts of a representative type of box before the parts are assembled and sealed;
- Fig. 2 is a perspective view of the form for assembling and sealing the boxes;
- 10 Fig. 3 is a view in section on lines 3—3 of Fig. 2;
- Figs. 4, 5 and 6 are views illustrating successive steps of assembling and sealing the boxes;
- 15 Fig. 7 is a view illustrating a modification of a step of assembling and sealing the boxes;
- Figs. 8 and 9 are detail views of a modified form of the assembling and sealing device;
- 20 Fig. 10 is a perspective view of the adhesive applying devices.
- The invention is here shown as applied for assembling and sealing paper boxes of a common type used for distributing food products, as crackers or the like, which are subject to rapid deterioration when exposed even slightly to the atmosphere or moisture. The common practice is to use moisture proof box material, treated to render the same impervious to moisture, atmospheric action, vermin etc., to assemble the end panels or bottom of the box with staples, then joining corners of the lids with staples and finally fastening the lid to the body manually with strips of adhesive tape.
- 25 This method even with the use of the impervious box material is not effective to accomplish the purpose intended, to-wit, to protect contents from atmospheric action, and moisture, for the reason that where the joints are formed with staples on the bottom of the box, and also the described method of fastening the lid to the body of the box permits crevices through which the moisture, atmosphere, vermin etc., will penetrate to the contents, thus negativing the good qualities of the box material used.
- 30 The objects attained in the invention consist of means and method for assembling and sealing the boxes which effectively overcome these objections. Box material can be used of a cheaper grade and by more effective sealing produce a better result than is attained by the present practice.
- To this end the food manufacturer or distributor is supplied with box material, as illustrated in Fig. 1, the several parts, consisting of the body and covers for the box, being furnished flat, or knocked down, the bodies of the boxes being formed into open end tubes.
- 35 Suitable forms as illustrated in Figs. 2 and 8, are provided for assembling and sealing the boxes, the same consisting of a frame 1, shaped to conform to the shape of the boxes, being larger than the boxes to permit of seating the same in the frame. A series of spring pressure devices 2, as shown in Fig. 2, or 3, as shown in Fig. 8, are arranged on the inner walls of the frame which act to shape the covers 4 and seal the same over the open ends, or top and bottom, of the bodies 5 of the boxes, as the same are seated in the frame.
- 40 The sealing flaps —*a* of the box covers are first rendered adhesive by passing the same over adhesive applying devices —*A*, as illustrated in Fig. 10, these devices being of any suitable form. As here shown, two of the devices are used, spaced one from the other to permit of applying the adhesive on two opposite flaps —*a* at the same time. The covers 4, being square as here shown, the four sealing flaps can be rendered adhesive by two movements over the devices by turning the covers a quarter turn for the second application.
- 45 Adhesive is also applied to the box covers, adjacent the flaps —*a*, as illustrated at —*b* in Figs. 1 and 10, to seal the flaps —*c* of the bodies of the boxes, double sealed joints being thus formed along all edges of the boxes.
- 50 The covers are then placed on the frame 1, being supported on the pressure devices 2, as shown in Fig. 4. The bodies —5 of the boxes are then set on the covers and both parts are pressed downward until the same are fully seated in the frame, the pressure devices 2, or 3, as the case may be, acting to shape the covers over the lower ends of the boxes and, at the same time, to effect sealing of the joints on the four sides of the box.

Following the first step of assembling and sealing the boxes, before the assembled unit is removed from the frame 1, the contents are placed in the box. The opposite end of the box is then closed and sealed in the same manner by removing the filled box, inverting and reseating the same in the frame over the opposite cover —a. In a modified form of the method, the second cover —a may be placed over the filled box and another frame —1 applied thereto, inverted as illustrated in Fig. 7, which has the effect of assembling and sealing the second cover of the box.

In either method here shown for assembling and sealing the boxes sufficient time elapses in forming, filling and sealing the boxes to permit the adhesive to set so that firm joints result. If desirable several sets of the assembling frames may be used to permit of leaving the sealed boxes in the frames longer, after the same have been filled for permitting the adhesive to set.

It will be obvious that the boxes can be filled with the bottoms unsealed and supported as illustrated in Fig. 4 and that the boxes can then be sealed simultaneously, at top and bottom, by using two of the assembling forms as illustrated in Fig. 7.

The two forms of pressure devices shown in the drawings—the curved flat springs 2 with the spring adjusting members 6, as best shown in detail Fig. 3, or the extended coiled springs 3, with the spring adjusting members 7, for regulating the tension of the springs, as shown in Fig. 9, are representative of any suitable pressure devices for forming adhesion of the joints along their entire lengths.

Having described my invention, I claim:

1. Means for sealing boxes consisting in a supporting member, a pressure element arranged on said member to define a space conforming to the shape of the boxes, adapted to support adhesive treated covers for the boxes, for receiving the covers and said boxes therebetween, and acting to form and seal said covers over the boxes, as the same are seated in said space.

2. Means for sealing boxes consisting in a plurality of supporting members, adapted to be placed in inverted relation one relative to the other, a pressure element arranged on each member to define a space conforming to the shape of the boxes, and to be disposed relative to adhesive treated covers of the boxes for receiving the covers and said boxes therebetween and each acting to form and seal said covers over the boxes, as the same are pressed into said spaces.

3. Means for sealing boxes consisting in a supporting member a plurality of adjustable, spring-tensioned pressure elements arranged to define a space conforming to the shape of the boxes, adapted to support ad-

hesive treated covers for the boxes, for receiving the covers and said boxes therebetween, for exerting pressure yieldingly thereon and acting to form and seal said covers over the boxes, as the same are seated in said space.

4. The herein described method of assembling, filling and sealing boxes consisting in positioning adhesive treated covers for the boxes relative to pressure elements arranged to define a space conforming to the shape of the boxes, in placing open ended bodies of the boxes upon said covers, in causing said elements to act to form and seal the covers over the boxes by seating the same in said spaces, in filling the boxes and in like manner assembling and sealing the covers over the opposite ends of the boxes.

5. The herein described method of assembling, filling and sealing boxes consisting in positioning adhesive treated covers for the boxes relative to pressure elements arranged to define a space conforming to the shape of the boxes, in placing open ended bodies of the boxes upon said covers, in causing said elements to act to form and seal the covers over the boxes by seating the same in said space, in filling the boxes, in positioning covers over the opposite ends of the boxes and in positioning a second unit of said pressure elements over said second covers and in like manner effect assembling and sealing of the same over the boxes.

6. The herein described method of assembling, filling and sealing boxes consisting in providing a plurality of sets of box assembling and sealing devices comprising pressure elements arranged to define spaces conforming to the shape of the boxes, in positioning adhesive treated covers for the boxes relative to a unit of each set of said devices, in placing open ended bodies of the boxes upon said covers, in causing said elements to act to form and seal the covers over the boxes by sealing the same in said space, in filling the boxes, in positioning covers over the opposite ends of the boxes and in positioning a second unit of each set of said devices over said second covers and in like manner assembling and sealing the covers over the opposite ends of the boxes, the interval of time between filling and sealing the boxes assembled in the different sets acting to effect firm adhesion along the entire lengths of the joints of the covers.

7. The herein described method of assembling and sealing paper boxes consisting in rendering covers for the boxes adhesive, the covers having sealing flaps adapted to be disposed outwardly of the box, and positioning the same relative to pressure elements arranged to define a space conforming to the shape of the boxes, in placing open ended bodies of the boxes having inwardly extended flaps adapted to be joined ad-

hesively to said covers and in effecting double sealed joints between said covers and bodies by pressing the same into said space.

8. The herein described method of filling and sealing boxes consisting in positioning adhesive treated bottom covers for the boxes relative to pressure elements, in placing open ended bodies of the boxes upon said covers, in filling the boxes, in positioning adhesive

treated top covers upon said bodies, in positioning a second unit of said pressure elements relative to the top covers, and in sealing the boxes by moving the pressure units one relative to another.

In testimony whereof, I affix my signature.

SAMUEL BERGSTEIN.
